United States Patent Office

Des. 190,512
Patented June 6, 1961

190,512

STRAINING DEVICE

Julia Ayala, 610 W. 110th St., New York, N.Y.

Filed Nov. 27, 1959, Ser. No. 58,493

Term of patent 14 years

(Cl. D44—29)

Fig. 1

Fig. 3

Fig. 2

FIGURE 1 is a perspective view of a straining device embodying my new invention, as it appears in use. The broken line showing of the glass is included for environmental purposes;

FIGURE 2 is a top plan view of a straining device; and

FIGURE 3 is a vertical sectional view, taken on the line 3—3 of FIGURE 2, with the hub portion shown in full lines.

I claim:

The ornamental design for a straining device, as shown and described.
